(57) **CLAIM**

The ornamental design for a advertising folding desk or table, as shown and described.

DESCRIPTION

FIG. 1 is a front and right perspective view of an advertising folding desk or table, showing my new design; the broken lines showing the changeable advertising sign are for environmental purposes only and form on part of the claimed design;

FIG. 2 is a front elevational view of the advertising folding desk or table of FIG. 1;

FIG. 3 is a top view of the advertising folding desk or table of FIGS. 1-2;

FIG. 4 is a side elevational view of the right side of the advertising folding desk or table of FIGS. 1-3;

FIG. 5 is a perspective view showing the left end and rear of the advertising folding desk or table of FIGS. 1-4;

FIG. 6 is a rear elevational view of the advertising folding desk or table of FIGS. 1-5.

FIG. 7 is a side elevational view of the left side of the advertising folding desk or table of FIGS. 1-6;

FIG. 8 is a bottom view of the advertising folding desk or table of FIGS. 1-7;

FIG. 9 is a rear elevational view of the advertising folding desk or table of FIGS. 1-8 shown in its unfolded position; FIG. 10 is a top view of the advertising folding desk or table of FIG. 9.

FIG. 11 is a side elevational view showing the left side of the advertising folding desk or table of FIGS. 9 and 10;

FIG. 12 is a bottom view of the advertising folding desk or table of FIGS. 9-11.

FIG. 13 is a front elevational view of a second embodiment of the design in its folded position;

FIG. 14 is a top view of the advertising folding desk or table of FIG. 13;

FIG. 15 is a side elevational view of the left side of the advertising folding desk or table of FIGS. 13 and 14;

FIG. 16 is a rear elevational of the advertising folding desk or table of FIGS. 13-15.
